UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,890, dated November 14, 1893.

Application filed October 7, 1893. Serial No. 487,511. Term of patent 3½ years.

To all whom it may concern:

Be it known that I, CHARLES BOOZE, a citizen of the United States, residing at Buffalo, in the county of Erie and State of New York,

5 have invented and produced a new and original Design for Wall-Paper, of which the following is a specification.

The design consists of a conventionalized form of the tulip forming ornaments arranged 10 at regular distances over the surface of the paper as represented in the accompanying drawing. In the border or upper portion of the design these ornaments are connected by scrolls and leaves and flowers of the tulip arranged 15 in a conventionalized form as shown in the drawing. The border is separated from the hanging by a horizontal band composed of parallel lines and small ornaments as shown.

What I claim is—

1. The design for wall paper herein shown and described.

2. In the design for wall paper the border herein shown and described.

Witness my hand this 2d day of October, 25 1893.

CHARLES BOOZE.
